CATHODE FILAMENT CONTROL FOR X-RAY
TUBES

Harry B. McEuen, Jacksonville, Fla.

Application March 13, 1934, Serial No. 715,340

3 Claims. (Cl. 250—35)

This invention is directed to an improvement in X-ray apparatus, and particularly to the cathode thereof to provide for focusing and concentration of the cathode-filament stream relative to the anode.

It is well understood that the input energy is limited by the heat of the anode in the predetermined focal area, and that provision has been heretofore made for permissible increase of such energy by mechanical cooling of the anode. While such cooling is of material benefit in the desired direction, it obviously does not and cannot permit the use of the ultimate amount of energy permissible for a given focal area of the anode. If, in addition to a proper cooling of the anode, the cathode stream is focused for focal area and at the same time distributed equally over such area, to avoid undue heat at any one part of such focal area, the input energy may be increased toward the permissible maximum without liability of objectionable heat effects on the anode.

The primary object of the present invention is, therefore, the provision of means whereby the cathode stream may be controlled mechanically and selectively for focusing and concentration or distribution.

A further object is the provision of the adjusting means for control and operation at any time without in any way affecting or interfering with the vacuum condition of the tube.

A further object is the provision of adjusting means arranged wholly within the tube and normally locked against operation, together with magnetic means arranged wholly outside of the tube and selectively operable to withdraw the lock of and operate the adjusting means.

The invention is illustrated in the accompanying drawings, in which:—

Fig. 1 is a broken longitudinal section of the cathode tube, illustrating particularly the adjusting means for the filaments.

Fig. 2 is a face view of the cathode.

Fig. 3 is a section on the line 3—3 of Fig. 2.

Fig. 4 is a longitudinal section of the cathode stem.

Fig. 5 is a broken elevation showing a modification.

Fig. 6 is a diagrammatic view showing the relation of the improved cathode and the anode to illustrate the control of the cathode stream.

Fig. 7 is a detail view showing adjustment finder.

The X-ray tube illustrated is of the general construction described and claimed in my co-pending application filed December 18, 1933,

Serial Number 702,989, and while such construction is preferable, or at least desirable, it is to be understood that the details hereinafter described are applicable to any construction of tube or of cathode stem.

To facilitate an understanding of the present invention, the X-ray tube may be briefly stated to include a tube or casing 1, in which is arranged a cathode stem and assembly 2, and an anode stem 3. The tube proper is made in sections, assembled in a manner to permit the interior of the tube to be subjected to the necessary vacuum, and the cathode stem, with which the present invention is more particularly concerned, is formed adjacent the filament or anode end with an insulating and seal-off section 4, preferably of glass, as in Fig. 1.

In connection with the details of the present invention, the cathode assembly includes a cathode stream distributing cup 5, having a wall 6, of any desired or appropriate outline, such wall being shown as of square outline in Fig. 2. This wall is arranged substantially parallel to the axis of the stem, and is connected to a rear wall 7, substantially at right angles to the stem axis. The rear wall 7 is provided with a rearwardly-extending sleeve 8, which slidably fits on and is guided by a conforming extension 9 projecting forwardly from the insulating and seal-off section 4. The distributing cup is thus mounted for sliding movement longitudinally of the stem, and while the type of mounting described is desirable, it will be understood that any conventional or preferred slidably-guided and supporting mounting may be used.

Arranged within the cup 5 is a cathode comprising a series of filament cups 10, one for each filament. The filament cups are formed by parallel flat sections 11, spaced apart and connected at their rear ends, as at 12, all as shown in Figs. 2 and 3. These cups are connected to high potential bar 17, but are not connected electrically to either of the filament bars 18 or 19, but support these bars on insulators and carry them forward and backward with adjustment of the filament cups. The auxiliary cups are movable as a unit within the main cup and are supported for such movement and to avoid undue friction by rollers or like elements 13, arranged between the distributing and auxiliary cups.

The filament cups have a rearwardly-extending bar-like member 14, which passes through the rear wall 7 of the main cup and is fixed at its rear end in an insulating disk 15, slidable in an insulating sleeve 16, connected to the sleeve 8

of the main cup. A high potential rod extends transversely of and across all auxiliary cups 10, being arranged near the rear of such cups. Similar filament rods 18 and 19 are carried by the filament cups near the upper and lower ends thereof, the rods 18 and 19 being directly supported in insulators 18' carried by the cups. The high potential lead 20 leads from the rear end of the stem to and through the seal-off section 4, thence through and fixed in disk 15, then through and fixed in bar 14, and is electrically connected to the high potential rod 17. The filament leads 21 and 22 extend in parallel relation to the high potential lead, being secured in the disk 15, and are connected to the rods 18 and 19. In the preferred form all leads are fixed or embedded in the seal-off section 4, in the disk 15, and preferably pass through insulating bars 15', to prevent possible short circuit between the leads. The leads throughout an appropriate portion of their lengths are, in the preferred form, of sinuous or convolute form, as at 20' in Fig. 1, to permit longitudinal adjustment of such leads without interfering with current flow. It will be noted that just beyond the sinuous formation toward the filament cups, all leads are fixed or embedded in the insulator disk 15, and that after passing through this disk the high potential lead 20 terminates at rod 17, while the filament leads 21 and 22 terminate at rods 18 and 19, respectively.

The rods 17, 18, and 19 carry the filaments 23, there being one such filament in each filament cup, as shown in Fig. 2. The axial length of the wall 6 of the distributing cup is greater than the similar dimension of the filament cups, and it will be obvious that the spread of the cathode stream may be varied by the axial relation of the distributing and filament cups. Obviously, also, the adjustment of the filament cups relative to the anode will serve a focusing function. If, therefore, means are provided by which movement of the distributing and filament cups can be selectively controlled, the focusing and also the spread or concentration of the cathode stream can be governed. It must be remembered, however, that the cathode stream is in a vacuum, which must not be disturbed, and also, to be commercially effective, the selective adjustments must be available at all times. This provision forms one of the essential features of the present invention.

To provide for the selective adjustment of the filament cups for focusing, the bar member 14 is formed with rack-teeth 24, and supported in bearings 25, carried by the main cup 5, is a shaft 26, on which is fixed a pinion 27 for cooperation with such rack. The shaft is either of insulating material, or is made in sections, connected 60 by an insulating sleeve. The lower end of the shaft terminates adjacent the wall of the tube 1.

It is desirable that means be provided for locking the shaft against rotation when not in use, for which purpose the lower bearing 25 is formed 65 on its lower surface with teeth 29, and the shaft below the bearing is provided with a disk 30 having similar teeth. The shaft is mounted for limited vertical movement, and on the side above the bearing is provided with a fixed collar 31, 70 between which and the bearing is a spring 32. The shaft, when free of other influence, will be moved by the spring 32 to interfit with the teeth on the disk and the teeth 29, thus holding the shaft against rotation.

75 The sleeve 8 or equivalent projection from the

distributing cup is also provided with a rack 33, with which cooperates a pinion 33', carried on a shaft 34, supported in bearings from the extension 9 of the seal-off section 4. This shaft, if made in sections has an insulating connection 5 at 35', and the shaft may, and preferably is, provided with locking means similar to that described in connection with shaft 26, though such is not illustrated.

The shafts 26 and 34 terminate at their lower 10 ends in a bar or disk 36 of magnetizable material. Arranged for cooperation with the disks 36 are operators, including rotatable shafts 38, having an operating handle 39 at the lower end. The upper end of each shaft is provided with a magnet 40, either permanent or electromagnet, which will, if appropriately positioned and operated, compel movement of either shaft 26 or 34, as selected, and thus compel the desired adjustment of the parts described. The magnets are preferably mounted for appropriate cooperation with the selected disk 36, and are designed to be turned out of influencing relation on the disks. The manually-operable rods for turning the magnets are of course to be of properly insulating 25 construction, in order to protect the operator against shock during operation. Each disk is appropriately marked with edge markings at 36', which cooperate with a mark 37' on the tube 1, to permit successive adjustments of identical 30 range, or initial adjustment according to predetermined requisites. The mark 37' for the disk 36 on the shaft 26 is of sufficient length to cooperate with the markings of that disk in any position assumed incident to the adjustment of the 35 main cup 5.

When it is desired to adjust the filament cups for focusing the cathode stream on the anode, the operator will move the magnet 40, or the appropriate magnet if more than one is used, into 40 magnetizable influence on the disk 36 of the shaft 26. The initial effect is to move the shaft longitudinally and thus release the lock. The magnetic influence then fixes the shaft and operating shaft, and by turning the latter the filament cups 45 may be moved in either direction. A similar operation in connection with shaft 34 will adjust the main cup.

The rack and pinion connection between the shafts 26 and 34 and the controlled parts, is 50 intended to be a conventional illustration of any and all appropriate means for accomplishing this result, it being understood that the purpose is to provide a minute and easily controlled cooperation, and any means to this end is contemplated. 55 Furthermore, the locking means may be in any conventional or desired form, so long as it is automatically serviceable when the operation is not desired and releasable when initiating such operation.

If desired the glass insulating and seal-off section 4 of the cathode stem may be provided with embedded metallic sleeves 41, and the leads, filament and high potential, divided to permit adjustment, as indicated in Fig. 5. These leads, indicated in Fig. 5, at 42, 43, and 44, may thus be of usual wire construction, and to insure electrical continuity at all times, each sleeve 41 is additionally connected to the movable portion of the lead therein by a spring conductive strip 45.

The general construction of the cathode assembly will be to avoid any sharp edges, except possibly in or on the anode-facing edges of the filament cups, where it may be found that needle-like, short points will be formed to point 75

directly toward the anode and project but a very slight distance beyond the main surface of the cup edges. This detail of the filament cups is an optional construction of the present invention, 5 but if used it will help electron emission at the higher voltages and yet be controllable in being directed at the focal area on the anode by the focusing cups. In providing a construction to avoid coronal discharge, it being understood that 10 at the higher voltages electron emission will take place from all rough, sharp surfaces, the edge of wall 6 of the distributing cup 5 will be rounded, and a skirt portion 46 will be extended rearwardly in line with such wall 6 for the full 15 length of the sleeve 8. This skirt will of course be formed with slots to provide for shafts 26 and 34, this skirt providing an electrostatic shield covering all sharp points and edges otherwise and necessarily present. All exterior surfaces, 20 particularly of the shield will be highly polished and rounded to prevent electron emission from undesired portions of the cathode.

With the construction described it is apparent that any predetermined or required adjustment 25 of the filament cups or of the distributing cup, or both, may be readily and easily secured at any time, without loss of vacuum or disconnecting any of the parts, and also while the X-ray tube is in actual use. The capability of adjustment provides for a very fine focus or a large focal area 30 on the anode. By the use of the scaled disk and fixed line, any previous adjustment can be subsequently obtained without difficulty. Thus one tube can be used for the lowest, highest, or any 35 intermediate milliamperage, with selected points of adjustment for a predetermined energy.

Through the described control the cathode stream is evenly distributed homogeneously over the face of the anode throughout the selected 40 focal area, thus avoiding any centralization of the heat.

The invention, while described in connection with a cathode of an X-ray apparatus with multiple filaments, is equally applicable to other 45 vacuum tubes, as for example, rectifier tubes and the like, and is also equally effective with one or any number of filaments.

The essential results of the construction described is the ability for adjusting in a tube of 50 this character the size of the focal area on the anode and the distribution of the cathode stream relative to the selected focal area. Thus no small area is forced to carry practically all the wattage employed, but a more or less even distribution of 55 the heat is secured over the selected focal area, and the more perfect this distribution the more possible the use of the ultimate amount of energy allowable for a given focal area on the anode.

While the cathode proper is shown as comprising the filament cups with their filaments, it 60 is obvious that the invention may be practiced with the use of other types of cathodes. However, the construction of the cathode disclosed herein is preferred, and results in outstanding advan- 65 tages.

Having thus described the invention, what is claimed as new is:

1. In a device of the character described, a casing sealed from the surrounding atmosphere, an anode in said casing, a cathode distributing 5 cup mounted within said casing for longitudinal movement with respect thereto toward and from said anode, means within said casing for moving said cup longitudinally thereof toward and from said anode to selected positions with respect thereto, said means including a magnetizable member positioned adjacent the inner wall of said casing, a cathode carried by and within said cup, whereby said cup controls the distribution of the cathode stream, and means wholly external of said casing including a magnet located adjacent the outer wall thereof in alignment with said member for actuating said first named means, whereby said cathode is simultaneously moved to said selected positions with said cup. 20

2. In a device of the character described, a casing sealed from the surrounding atmosphere, an anode in said casing, a cathode mounted within said casing for longitudinal movement with respect thereto toward and from said anode, means 25 within said casing for moving said cathode toward and from said anode to selected positions with respect thereto, said means including a magnetizable member positioned adjacent the inner wall of said casing, and means wholly external of said casing including a magnet located adjacent the outer wall thereof in alignment with said member for actuating said first named means. 30

3. In a device of the character described, a 35 casing sealed from the surrounding atmosphere, an anode in said casing, a cathode distributing cup mounted within said casing for longitudinal movement with respect thereto toward and from said anode, means within said casing for moving 40 said cup longitudinally thereof toward and from said anode to selected positions with respect thereto, said means including a magnetizable member positioned adjacent the inner wall of said casing, actuating means wholly external of said 45 casing and operable therethrough for actuating said first named means, said actuating means including a magnet located adjacent the outer wall thereof in alignment with said member for actuating said first named means, a cathode 50 mounted within said cup for movement independently thereof toward and from said anode, means within said casing for moving said cathode independently of said cup toward and from said anode to selected positions with respect thereto, 55 said last named means including a second magnetizable member positioned adjacent the inner wall of said casing, and actuating means for said last named means located wholly externally of said casing and operable therethrough, said last 60 named means including a magnet located adjacent the outer wall thereof in alignment with said second named member.
